UNITED STATES PATENT OFFICE

FRANCISCO QUINTANA MIRANDA, OF CORDOBA, ARGENTINA

MUTE FOR STRINGED INSTRUMENTS

Application filed December 30, 1928, Serial No. 417,502, and in Argentina November 28, 1929.

My invention relates to a damper or blender for stringed instruments which enables the performers on musical instruments, such as the fiddle, violin, viola, violoncello and bass, to deaden or augment the sound of the instrument while they are playing, without any interruption in the execution. The damper or blender, when applied, gradually permits the blending of some phrases or musical passages, and if suddenly applied contrary musical effects are obtained. It is likewise an original recourse for musical composers, since these have greater facility for expressing, with combinations of new sounds, their delicate, expressive, sentimental, etc. inspirations.

In order that the invention may be better understood, it is illustrated by various figures in the accompanying drawings:

Figure 1 shows a fragmentary perspective view of a damper coupling constructed in accordance with the invention.

Fig. 2 is a similar view of the coupling, showing the same in a different position from that in Fig. 1.

Fig. 3 is a similar view, the position of the coupling being further changed.

Fig. 4 is a perspective view of one section of the damper.

Fig. 5 is a similar view of another section.

Fig. 6 is a perspective view of the damper element.

Fig. 7 is a similar view of the same in another position.

Fig. 8 is a perspective view of coupling sections and damper element assembled for application to a violin.

Fig. 9 is a perspective view of a modified form of damper for use with violoncello, the damper section being fragmentarily disclosed in dotted lines.

Fig. 10 is a perspective view of a coupling member used therewith.

Fig. 11 is a fragmentary detail of the lug for the coupling member in Fig. 10.

Fig. 12 is a perspective view of the foot actuator for the damper shown in Fig. 9.

Fig. 13 is a perspective view of a violin showing the damper illustrated in Fig. 8 applied thereto.

Fig. 14 is a perspective view of a violoncello with the damper illustrated in Fig. 9 applied thereto and also the foot actuator.

Referring to Figs. 1 to 8 and 13, the apparatus is composed of the members A, B, C and D: a coupling A is attached to the instrument by means of the string N which is stretched from the string-bar to the button on the body of the violin, which string is passed over and about the grooves a in the cross piece o in Figs. 1 to 3. This coupling has at its upper portion a flattened sleeve c, in which is inserted a flat curved spring of steel e (Fig. 4). The lower portion d, which rests on the instrument, has fastened to it a small piece of cloth, skin, cork, etc. A metal bar b, in its small end, has partly attached thereto by means of solder, small screws or rivets etc. the steel spring e which is curved and fitted in the flattened sleeve c, before described. At the other end of the said bar b there is a socketed enlargement g, wherein is placed the shank k of another section h of the bar C, the other or free end of this bar h being in the form of a hammer having a groove or slot i. On the end k of the said bar is glued a small piece of suede, chamois-leather or other soft and fine skin, and intersecting the groove or slot i is a hole j, in which is driven a nail or screw for the purpose of holding firm in the groove or slot the damper or blender saddle D which will be referred to later on. The sections of the bar indicated by B and C, Figs. 4 and 5, should be well fastened with glue, secatine or other similar material when fitting the shank k in the socket g. The sections referred to can be made of one whole piece of metal, wood or other material; but I consider the procedure above indicated preferable. The damper or blender saddle D is preferably made of a thin steel plate, flexible in its central portion and thickened at its extremities; these ends can also be of other metal, soldered to the steel plate that forms the central portion and the saddle D, taking approximately the form of the larger part of the bridge of the instrument to which it is applied, in order that the said bridge may be sustained when the damper or blender is used. To the inner

100

faces of the ends 1 and 1' of the damper D is glued a small piece of soft and fine skin. This saddle is fitted in the groove or slot *i* in the wooden bar mentioned above, and has 5 an orifice *m* through which the nail is passed, preferably a glued wooden nail or screw driven into the hole *j* in the wooden bar. The portion of the said saddle D which is fitted in the groove or slot *j* in the wooden bar 10 should also be glued.

When the damper or blender is employed on violoncello or basso, reference being now had to Figs. 9 to 12 and 14, there should be fitted two shaft supports *p* on the body of this 15 instrument, the supports being carried by the plate E. A coupling axle F rests in these supports, to which axle is attached a curved bar G, which carries at its small forked end two small shafts or fixed rings *q*, *q'*, through 20 which pass two hooks *r*, *r'* which are held to a small plate S, the latter having at its lower end another ring Z from which is suspended a bar or cord *y'* which is joined to another ring *t* at the extremity of a foot treadle in the 25 form of bar or long-iron T. This bar acts as a pedal and has at its other extremity a small cross-plate *u*. Each of the ends *v*, *v'* of the curved bar G has attached thereto the wires *w*, *w'*, which are also engaged on the axle F 30 and serve the purpose of braces for strengthening the fork of the bar and impeding the loss of its firmness. The end Z' of the curved bar G bears on lever Q of the damper. The center of the fork of this bar carries a graduated screw U, whose extremity *y* is against 35 the instrument, preventing the curved bar G from failing to press on the bar G of the damper or blender, and the latter from separating too much from the bridge of the instrument when no pressure is made with the 40 pedal. The size of the damper or blender is in relation to the size of the corresponding parts of the bow musical instruments previously mentioned. P is the floor support.

45 When the damper or blender is applied to the violin, the operation of the same is as follows:—

The violist inclines his head slightly towards the right and with his chin, presses more or less (according to the expression required for the piece he is playing) on the metal plate *b*, which, in turn, by reason of the fact that it is joined to the smaller end *k* of the section C and the thickened ends *l*, *l'* of 50 the saddle D' which are normally spaced from the bridge, but near thereto, presses the saddle D against the bridge L and, as a consequence, he modulates or augments the tones of the instrument that is being played. On ceasing 55 the pressure with the chin, gradually or suddenly, with the head assuming its original position, the damper or blender is raised under the action of the curved spring *e* which is attached to the sleeve of the coupling. When 60 the damper or blender is employed on violon-

cellos or bassos, the operation is produced by means of the pedal T which, on being pulled by means of a bar or cable *y'* of the smaller part of the curved bar G, causes the latter to move on its axle F and the larger part Z' to 70 press on the bar Q and this in turn, with the other elements previously mentioned, produces, through the pressure on the bridge L of the instrument, the effects aforementioned.

75 I claim as my invention:

1. A mute for a stringed musical instrument, comprising a coupling pivoted at the tail of the instrument, an arm connected to the coupling, a damper saddle attached to the other end of the arm and adapted to contact 80 with the bridge of the instrument, means for resiliently flexing the arm to keep the saddle normally out of contact with the bridge, and means controlled by the player for overcoming the resilient means and for contacting the saddle with the bridge, the whole attachment being movable about the coupling as pivot.

2. A device as set forth in claim 1, wherein the coupling comprises a hollow sleeve, and the arm comprises a curved spring which is 85 inserted into the sleeve.

3. A device as set forth in claim 1, wherein the arm comprises a plurality of interlocking members.

4. A device as set forth in claim 1, wherein 90 the damper saddle is attached to the arm by means of a slot in the arm into which the saddle is inserted, and a hole and pin passing through the arm and the saddle.

5. A device as set forth in claim 1, wherein 95 the saddle comprises a two-armed member which is thickened at the extremities of the arms.

6. A device as set forth in claim 1, wherein 100 the means for contacting the saddle with the bridge is operable by the foot of the player.

7. A device as set forth in claim 1, comprising means for adjusting the resilience of the flexing means.

105 In testimony whereof I affix my signature. 110
FRANCISCO QUINTANA MIRANDA.
